Corporation, Chicago, Ill., a corporation of the
United States

Application November 21, 1935, Serial No. 50,952

5 Claims. (CL 62—89)

This invention relates to a refrigerator cabinet construction and more particularly to a utility shelf combined with a door of the refrigerator cabinet.

5 It is sometimes desirable to rearrange the position of dishes and the like on the shelves in the cooling compartment of a refrigerator. When the shelves are crowded with dishes, difficulty is often experienced in holding one or more of the 10 dishes while arranging others.

In accordance with this invention a utility shelf is provided which is attached to a door of a compartment disposed below the cooling compartment of a refrigerator. This compartment may 15 be the one used to house refrigerating apparatus. When the door is opened this shelf slides out and provides a convenient place for resting certain dishes while rearranging or removing others from the cooling compartment.

20 Objects of this invention will be apparent to those skilled in this particular art from the claims and the description in the specification taken in connection with the drawing in which:

Fig. 1 is a perspective view of a refrigerator and door illustrative of this invention.

Fig. 2 is a fragmentary sectional plan view of an illustrative embodiment of this invention.

Fig. 3 is a fragmentary sectional front elevation of a structural detail of this invention.

30 Fig. 4 is a fragmentary sectional elevation of the apparatus compartment of the refrigerator of Fig. 1, the refrigerating equipment being omitted for the purpose of clarity.

Fig. 5 is a front elevation partly in section of 35 the structure shown in Fig. 4.

In the embodiment of the invention which has been chosen for the purposes of illustration in Fig. 1 is shown a refrigerator 10 having an upper or cooling compartment 11 with the evaporator 40 or analogous cooling unit 11a therein and a lower or apparatus compartment 12 mounted on a base 13. The apparatus compartment 12 houses conventional refrigerating equipment generally indicated at 12a and has a door 14 pivotally secured 45 proximate the lowermost portion of the base 13. A shelf 15 is pivotally secured to the door 14 by means of links or brackets 16.

Referring now particularly to Figs. 2 to 5, the shelf 15 is made up of side members 17, a front 50 frame member 18, a rear frame member 19 and a suitable base portion 20 connecting the rear and front frame members and which may be in the form of a wire screen. Secured to the side of the apparatus compartment proximate its 55 uppermost portion are a pair of supports 22.

These supports are provided with grooves 23 facing the interior of the apparatus compartment and in which are slidably mounted the side frame members 17 of the shelf 15.

Referring now particularly to Fig. 2 it is seen 5 that the side member 17 extends beyond the grooved support and the rear frame member 19 is secured at a point intermediate of the ends of the side members, whereby, when the shelf is in open position, as shown in Fig. 1, goodly portions 10 of the side members 17 remain within the grooved supports and furnish a firm support for the shelf. This feature is clearly illustrated in Fig. 2.

Referring now to Figs. 1, 2, 4 and 5, a bracket 25 is secured to the door 14 and pivotally holds 15 one end of a link 16. The other end of each link is looped around or otherwise pivotally secured to each of the frame members 19 at 27. Secured to the ceiling of the compartment 12 is a limiting member 29 which may be in the form of a bar 20 having two downwardly projecting loops 30 disposed proximate but interiorly of the side frames 17. These loops are adapted to engage the rear shelf frame member 19 when the shelf is in 25 exteriorly extended position and due to their inherent resilience have a cushioning effect should the door be swung open violently.

Referring now particularly to Fig. 4 a bracket 32 is shown secured to the front of the base portion 13 and consists of a main and downwardly 30 extending portion 33 bolted or otherwise secured to the inner face of the front of the base, a horizontal portion 34 bent forwardly of the base and a short upwardly extending portion 35. The upwardly extending portion 35 engages a grooved 35 portion 36 of the door 14 making a simple but effective pivotal juncture of the door with the base 13. Conventional resilient gaskets 37 are provided for the pivoted door and a conventional resilient catch 38 will hold the door snugly and 40 firmly in closed position against these gaskets.

A door opening member is provided that consists of a cam 40 pivotally secured to a side wall of the compartment 12 by means of a lug 41. A link 42 is pivoted to the cam 40 by a bent over 45 portion 43. At its lowermost portion it is bent and projects through the walls of the compartment to form a treadle 44.

In the operation of this device when it is desired to use the shelf one has merely to step 50 on the treadle member 44 which through the link 42 forces the elongated edge of the cam 40 against the inner face of the door and forces the door open against the action of the spring catch 38. By virtue of the grooved supports 22 55

and pivotal link connections 16 this movement of the door causes the shelf to slide outward in its grooved support until it is engaged by the limiting members 30. At this point the shelf will be in fully extended position. By pivoting the door 14 proximate the lowermost portion of the base 13 a longer radius is provided for the door from its pivotal point to the point where the links 16 are pivotally secured. This securing arrangement makes it possible to fully extend the shelf without undue swinging of the door.

A specific refrigerator and door structure has been described in some detail but it is to be understood that changes, additions, substitutions and omissions may be made in the structure herein shown within the spirit of the invention as defined by the appended claims.

I claim:

1. A refrigerator cabinet having a food storage compartment and an apparatus compartment beneath the food storage compartment with doors affording access to said compartments, a combined support and transfer shelf in the apparatus compartment movable out of the compartment to a position to support articles to be inserted into and articles to be removed from the food storage compartment, and a connection between the door of the apparatus compartment and said transfer shelf so that the shelf is brought into and out of operative position by the opening and closing of the door of the apparatus compartment.

2. Refrigeration apparatus comprising a food storage compartment and an apparatus compartment beneath the food storage compartment with doors affording access to said compartments, the door for the apparatus compartment being hinged along its lower portion so that when both doors are opened cold air settling from the food storage compartment will be deflected into the apparatus compartment, a combined support and transfer shelf in the apparatus compartment movable out of the compartment to a position to support articles to be inserted into and articles removed from the storage compartment, and a connection between the door of the apparatus compartment and the transfer shelf so that the shelf is moved into and out of operative position upon the opening and closing of the door of the apparatus compartment.

3. A refrigerator cabinet having a food stor-

age compartment and an apparatus compartment beneath the apparatus compartment with doors affording access to said compartments, and a combined support and transfer shelf in the apparatus compartment movable out of the compartment to a position to support articles to be inserted into and articles removed from the food storage compartment, guides in said apparatus compartment for supporting said transfer shelf, and means connecting the shelf and the door of the apparatus compartment whereby when the door of the apparatus compartment is opened the transfer shelf will be slid in a substantially horizontal plane outward to a position of use.

4. A refrigerator cabinet having a food storage compartment and an apparatus compartment beneath the food storage compartment with doors affording access to said compartments, a combined support and transfer shelf in the apparatus compartment movable out of the compartment to a position to support articles to be inserted into and articles to be removed from the food storage compartment, a connection between the door of the apparatus compartment and said transfer shelf so that the shelf is brought into and out of operative position by the opening and closing of the door of the apparatus compartment, and treadle means for opening the door of the apparatus compartment.

5. Refrigeration apparatus including a refrigerator cabinet having a food storage compartment and an apparatus compartment beneath the food storage compartment, doors affording access to said compartments, means for refrigerating the food storage compartment and thereby causing air circulation within said compartment, a combined support and transfer shelf in the apparatus compartment movable out of the apparatus compartment into article supporting position within cooling adjacency to said food storage compartment whereby articles on the transfer shelf will be cooled by flow of air from the food storage compartment when the door of the food storage compartment is opened, a connection between the door of the apparatus compartment and said transfer shelf so that the shelf is moved into and out of operative position upon the opening and closing of the door in the apparatus compartment, and means for cushioning movement of the shelf in one direction.

MATTHEW R. HULL.
